STUD DRIVING TOOL

Virginius E. Erickson, Portland, Oreg., assignor
to Powder Power Tool Corporation, Portland,
Oreg., a corporation of Oregon

Application March 2, 1951, Serial No. 213,549

7 Claims. (Cl. 1—44.5)

1

The present invention relates to stud driving tools of the type employed for the explosive installation of studs in various types of concrete and steel structures, and is concerned more particularly with apparatus adapted to employ a standard explosive charge and vary the effective force of such charge as applied to the stud to obtain the proper force for successful installation of a particular stud in a particular wall surface. This invention is concerned with power control method and apparatus of the general character disclosed and claimed in the copending application of Erickson and Bullwinkle, Serial No. 135,744 filed December 29, 1949, for Stud Driving Tool.

The present invention provides for varying of 15 the combustion space or chamber for the explosive charge and also for simultaneously varying the spacing from the muzzle end of the barrel to influence further the energy imparted to the stud. The invention employs an insert in the barrel of 20 the tool which is formed to provide for frictional retention of the stud at any desired location along the insert length.

The above and other objects of the invention are attained in connection with a preferred embodiment of the invention, as disclosed and described in connection with the accompanying drawing, in which:

Figure 1 is an elevational view of a stud driving tool with certain parts broken away and 30 shown in section to illustrate the combustion chamber of the tool.

Figure 2 is an enlarged view of a portion of Figure 1.

Figure 3 is a fragmentary enlarged view showing a stud held in place in the sleeve insert.

Figure 4 is a fragmentary perspective view of the sleeve insert.

Referring to Figure 1 there is shown a stud driving tool of the character described and claimed in the accompanying application of Smith and Daugherty, Serial No. 124,078, filed October 28, 1949, for Stud Driving Tool and Erickson and Bullwinkle, Serial No. 130,818, filed December 2, 1949, for Stud Driving Tool. In general, stud driving tools of this character are adapted to be separated or broken in two halves including a rear part 10 which contains the various firing control parts, including, for example, a firing pin carrier 11, and a front or barrel part 12 of the tool in which the barrel 13 is included. The barrel 13 is provided with an enlarged rear end 13A which has a threaded connection within the end of the firing pin carrier 11 to connect the two halves in the tool. Barrel 13 is also provided with

an enlarged bore in which a combustion chamber or breech plug insert 14 is provided for holding the cartridge 18 containing a standard explosive charge. Immediately adjacent the enlarged bore, a smaller enlargement of the bore extends down the barrel to receive a sleeve insert 19 which has a slight press fit therein to maintain its position.

The sleeve insert 19 has a plurality of holding fingers for a stud 16 and these fingers are formed 10 by a series of equally spaced spring members 19A which are struck out or formed in the wall of the tube 19. As shown there are two series of spring members 19A, providing respective fingers by which a stud may be frictionally held as shown in Figure 3, for example, where the stud has compressed a sleeve spring 19A. It will be noted that the spring fingers 19A of the two series are offset longitudinally of the sleeve to provide for retention of the stud at any desired location. The internal diameter of the sleeve retains the stud in axial alignment within the barrel.

In operation, the tool is broken in two halves by unthreading the barrel 13 from the firing pin carrier 11 and withdrawing the barrel from within the rear part 10. With the parts disassembled, the breech plug or insert 14 is removed and the stud 16 is installed in the sleeve 19 in engagement with the desired finger 19A. The stud may be positioned as disclosed in said application Serial No. 135,744. The cartridge 18 is placed in the breech plug 14, and the parts are reassembled as shown in Figure 1 for firing operation.

Firing is accomplished by placing the end of the barrel 13 against the surface in to which the stud is to be driven, and by pressing or telescoping the barrel 12 and firing pin carrier 11 back into the remainder of the tool until the firing position is reached, as disclosed in said applications, and then turning the rear end grip 21 with respect to the central housing 22 to fire the tool. At this time the deflector pad structure 23 mounted about the barrel 13 is engaged with the surface about the area of engagement of the end of the barrel so as to provide protection from flying particles of the wall surface upon explosive installation of stud.

As previously stated, the effective force of the standard explosive charge is varied by positioning the stud at different pre-determined distances along the barrel and in spaced relation with respect to the muzzle end of the barrel and with respect to the cartridge. In this way the volume of the combustion chamber is varied, and the effective length of the barrel thru which a stud is driven by the explosive charge is also

changed, and these two factors are combined in varying the power control to drive the stud.

While I have shown a preferred form of the invention, it is apparent that the invention can be employed in other ways so that its scope should be limited only by the scope of the claims appended hereto.

I claim:

1. In a stud driving tool, a barrel having a longitudinal bore therein enlarged at one end, a breech plug insert mounted in the enlarged portion of said bore, means in said breech plug for holding a cartridge, a sleeve member, means for seating said sleeve member in said barrel adjacent said breech plug insert, said sleeve member having a series of spring members for holding a stud in spaced relation to a cartridge in said breech plug insert.

2. In a stud driving tool, a barrel having a longitudinal bore therein enlarged at one end, a breech plug insert mounted in the enlarged portion of said bore, and a sleeve member seated in said barrel adjacent said breech plug insert having friction elements along its length for holding a stud in position.

3. In a stud driving tool, a barrel having mounting means at its breech end for a cartridge, and frictional retaining means mounted in said barrel as a part of the bore thereof and extending longitudinally of said barrel adjacent said breech end for holding a stud in any one of a plurality of desired selected positions with respect to the cartridge.

4. A stud driving tool as recited in claim 3, in which said frictional retaining means comprises a plurality of longitudinal series of frictional holding elements, said respective series being spaced circumferentially with respect to each other.

5. A stud driving tool as recited in claim 3, in which said frictional retaining means comprises a longitudinally disposed series of leaf spring members.

6. A stud driving tool as recited in claim 3, in which said frictional retaining means comprises a longitudinal series of obstructions mounted for movement in said barrel and transversely thereof, each obstruction being normally in an obstructing position within the bore of the barrel, and being movable by a stud to withdrawn position with respect to the bore.

7. In a stud driving tool, a barrel having a longitudinal bore therein enlarged at one end, a breech plug insert for mounting in the enlarged portion of said bore, and stud retaining means mounted in said barrel adjacent said breech plug insert comprising a longitudinal series of obstructions mounted for yielding movement transversely of the barrel.

VIRGINIUS R. ERICKSON.
